UNITED STATES PATENT OFFICE.

JAMES HENRY REID, OF NEWARK, NEW JERSEY.

ELECTRIC FURNACE.

947,849.

Specification of Letters Patent.

Patented Feb. 1, 1910.

Application filed May 8, 1909. Serial No. 494,876.

To all whom it may concern:

Be it known that I, JAMES HENRY REID, of Newark, in the State of New Jersey, United States of America, have invented certain new and useful Improvements in Electric Furnaces, of which the following is a specification.

My invention relates to improvements in electric furnaces, and the objects of my invention are to provide means for regulating the electrodes without undue loss of current, to provide means for retaining the ore on the electrodes until it has reached a determined degree of fluidity, further to provide means to receive the ore from the electrodes and separate the lighter from the heavier constituents. The regulation of the electrodes is carried out by means of galvanometer needles having co-acting contact points by means of which the current, through a regulating motor, for controlling the movement of the electrodes, may be reversed in direction to move the electrode either inwardly or outwardly.

In the particular embodiment of the invention illustrated, a longitudinally extending fixed electrode is provided, operating in combination with a plurality of adjustable electrodes on each side adapted to form a hopper to receive the ore, the space between the end of the adjustable electrodes being such that only ore in a more or less molten state may pass through, and the amount of this distance may be automatically regulated by the means hereinafter described. After the ore passes the electrodes, it is arranged to drop directly into a quenching tank provided in the bottom of the furnace, and means are there provided to separate the lighter from the heavier constituents. In the embodiment illustrated, a shaker plate is provided slightly below the level of the surface of the liquid, and a continuous stream of liquid is maintained over this shaker plate in a reverse direction to the inclination thereof, whereby the heavier constituents will by gravity, pass down the shaker plate in one direction, while the lighter constituents will be carried off by the stream of liquid. All these and other features of the invention are described hereinafter in detail in the accompanying specification and drawing.

In the drawings, Figure 1 is a longitudinal section through the furnace. Fig. 2 is

a transverse section through the same. Fig. 3 is a plan view of the needles and face plates on the galvanometer. Fig. 4 is a diagrammatic view showing the electrical connections.

In the drawings, like figures and letters of reference indicate corresponding parts in each figure.

Referring to the drawings, A represents the body portion of the furnace constructed of suitable material, such as masonry.

B represents the longitudinally-extending fixed electrode, that in the embodiment illustrated being horizontally-disposed and supported on a metallic beam 10 extending into the end walls 11 and 12 of the masonry structure.

C and D represent the adjustable side electrodes, of which there may be any suitable number from a single pair upward. These electrodes are preferably inclined as indicated, whereby they will form a hopper to hold the ore during treatment. The ends of these electrodes are adapted to be maintained a constant distance from the sides of the electrode B whereby when the ore reaches a desired degree of fluidity, it may pass through the space between. If desired, the electrode B may be provided with beveled faces 13 and 14, adapted to receive the ends of the electrodes C and D. In order to automatically maintain the electrodes this determined distance apart, mechanical, electrical regulating means are provided. In the embodiment illustrated, these means comprise a shaft 15 having a screw-threaded section 16 engaged with a collar 17 on the electrode, the opposite end of the shaft being provided with a worm 18 which engages a worm pinion 19 on a shaft 20, which shaft has a beveled gear 21 meshing with a beveled pinion 22 on the shaft of an electric motor E. This electric motor is preferably connected in shunt the current passing through the electrodes, and the regulation is effected by automatically reversing the current whenever the electrodes come too close or move too far.

The means which I have devised to accomplish this are illustrated diagrammatically in Figs. 3 and 4. In these figures, F represents a galvanometer having two synchronously operated needles a and b, the face of the galvanometer being provided with series of arcuate perforations c, d, e and f, arranged substantially in the path of the

opposite ends of the needles the said needles being centrally pivoted. On each of these, contact plugs *g*, *h*, *i*, *j*, *k*, *l*, *m* and *n* are provided adapted to fit into perforations, and adapted to be engaged by the needles when in certain positions, the electrical connection being shown in Fig. 4. Referring to this figure, *G* represents the main circuit including dynamo *o* and electrodes *p*. The galvanometer *F* is connected across the electrodes by conductors *q* and *r*. The plug *g* is connected to the plug *l*. The plug *h* is connected to the plug *k*. The plug *i* is connected to the plug *j*, while the plug *m* is connected to the plug *n*. The plug *g* is then connected by a conductor *s* with one side of the line, while the plug *h* is connected with the opposite side by a conductor *t*.

A conductor *u* connects the plug *i* with one side of the motor *E* while a conductor *v* connects the opposite side of the motor with the plug *m*. The connections having been thus made, and the pairs of plugs placed a determined distance apart so that connections will be made when the voltage exceeds the limit represented by the distance between the plugs, the operation will be as follows: If the needle starts at normal position, and the voltage through the electrodes begins to increase, which means that the distance between the ends of the electrodes is widening, the needles will finally come into the position illustrated in Fig. 4, connecting the plugs *i* and *h*, *l* and *m*. A part of the current of the dynamo *o* will then flow through the conductor *s* to the plug *l*, through the needle *b*, conductor *v* to the motor *E* through the conductor *u* to plug *i*, through the needle *a* to plug *h* and through the conductor *t* to the opposite side of the dynamo, operating the electric motor *E* and moving the electrode inwardly. As it does this, the voltage will drop and when it is moved below the determined limits the galvanometer needles will move to the reverse position connecting the plug *g* with the plug *j* and the plug *h* with the plug *n*. In this case, the current from the one side of the dynamo *o* will flow through the conductor *s* to the plug *g* through the needle *a* to the plug *j*, through the conductor *u* to the motor *E*, being thus connected to the opposite side of the motor to that to which it was connected previously. In passing through the motor, the current will pass through the conductor *v* to the plug *n*, through the needle *b* to the plug *h* and through the conductor *t* to the opposite side of the line. This will operate the motor in the reverse direction, effecting a withdrawal of the electrodes. There will thus be in operation, a continually reversing of the current through the motor *E*, the result of which will be to maintain the electrodes substantially in normal position.

65 When the melted ore, which, if desired,

may be partially reduced by the carbon of the electrodes, (or suitable reagent mixed with the ore) passes between the electrodes it is adapted to fall directly into the quenching tank *H* containing a suitable quenching liquid such as water, and means are provided for separating the lighter from the heavier constituents. The means I have illustrated to accomplish this, comprise a shaker plate *I* pivotally supported from links 23 and inclined downwardly toward the end 24 of said plate being located a short distance beneath the top of the surface of the liquid, and preferably being perforated whereby the water will offer less resistance to its movement. This plate may be reciprocated by any suitable means. In the form illustrated, a link 25 connects one of the links 23 with a crank 26 on the shaft 27 rotated by any suitable means. Above the shaker plate and near the end 24 a nozzle 28 is provided discharging toward the opposite end of the shaker plate and connected with a suitable supply pipe 29. The end 30 of the shaker plate extends above a trough 31 leading through the side of the furnace. The liquid discharging from the nozzle 28 will maintain a continuous stream over the surface of the shaker plate and out the trough 31 to any suitable settling tank, (not shown), and the lighter constituents of the ore, such as the slag will pass out through the trough 31, while the heavier constituents, such as the metals, will by gravity, roll down the shaker plate into the tank *H*, the quenching liquid causing the metal to solidify in the form of small globules. It will thus be seen that the apparatus above described provides a very simple means of effecting the reduction and separation of the valuable constituents such as the metals of an ore from the more or less valueless constituents such as the slag.

In using the furnace, the ore is first brought to a finely divided state and fed through a suitable hopper *J* on to the electrodes. It is here reduced both by the action of the electric arc and the carbon in the electrodes, and on dropping into the quenching basin, the lighter material and slag is carried away by the stream of liquid, while the heavier constituents collect in globular form in the quenching tank *H*.

As many changes could be made in the above invention and many apparently widely different embodiments of my invention, within the scope of the claims could be made without departing from the spirit or scope thereof, it is intended that all matter contained in the accompanying specification and drawings shall be interpreted as illustrative and not in a limiting sense.

What I claim as my invention is—

1. The combination, with suitable electrodes, of means therebelow adapted to re-

- ceive the material passing off the same and to separate the lighter from the heavier constituents. 45
2. The combination with suitable electrodes, of liquid-operated means adapted to receive the material passing off the same and to separate the lighter from the heavier constituents. 50
3. The combination with suitable electrodes, of a quenching tank below the same, having means for creating a current on the surface of the liquid to carry off the lighter constituents of the material, dropping into the same. 55
- 15 4. The combination with suitable electrodes, of a quenching tank below the same, an inclined shaker plate below the surface of the liquid in the quenching tank and means for creating a current of liquid over 60 the shaker plate. 65
5. The combination with suitable electrodes, of a quenching tank below the same, a foraminous shaker plate below the surface of the liquid in the quenching tank and means for creating a current of liquid over 70 the shaker plate. 75
6. In an electric furnace, the combination with the electrodes of a quenching tank below the same, into which the molten material passing through the electrodes is adapted to drop, and means for maintaining a condensed current of liquid in the top of the quenching tank to carry off the lighter constituents of the material dropping into 80 the same. 85
7. In an electric furnace, a fixed electrode and oppositely disposed adjustable electrodes above the same adapted therewith to form a hopper to receive the ore. 90
- 40 8. In an electric furnace, the combination with a fixed, longitudinally extending electrode, of a plurality of abutting, inclined electrodes on each side thereof adapted, therewith, to form a hopper to receive the ore. 95
9. An electric furnace comprising a suitable masonry structure having a longitudinally-extending beam, a fixed electrode supported on the beam, and adjustable electrodes forming with the fixed electrode a 100 hopper to receive the ore. 105
10. In an electric furnace, a pair of electrodes of opposite polarity adapted to retain unmelted material between their extremities, an electric motor mechanically connected to 110 one of the electrodes adapted to move the same inwardly and outwardly and means for reversing the current whenever the voltage exceeds determined limits. 115
11. In an electric furnace, a pair of electrodes of opposite polarity adapted to retain unmelted material between their extremities, an electric motor mechanically connected to 120 one of the electrodes adapted to move the same inwardly and outwardly, a galvanometer connected across the electrodes and means operated by the needle thereof for reversing the current. 125
12. In an electric furnace, the combination with an electrode, of an electric motor operatively connected to the electrode adapted to move the same outwardly and inwardly, a double needle galvanometer adapted to measure the current passing through the electrode and means operated by the needles 130 of the galvanometer for reversing the current whenever it passes a determined limit in either direction. 135

In witness whereof I have hereunto set my hand in the presence of two witnesses. 80
